Des. 208,220

Patented Aug. 1, 1967

208,220

LUNCH BOX OR SIMILAR ARTICLE

Lois Jean Frost, 13639 Hutchcroft St.,
La Puente, Calif. 91746

Filed Mar. 1, 1966, Ser. No. 1,233

Term of patent 14 years

(Cl. D58—17)

FIG. 1 is a perspective view of a lunch box or similar article showing my new design, wherein four fins are spaced about the lower half of the body;

FIG. 2 is a side elevational view thereof;

FIG. 3 is a top plan view thereof;

FIG. 4 is a bottom view thereof;

FIG. 5 is a reduced scale side elevational view of a lunch box or similar article showing another embodiment of my new design wherein three fins are spaced about the lower half of the body;

FIG. 6 is a bottom view of the embodiment illustrated in FIG. 5.

I claim:

The ornamental design for a lunch box or similar article, substantially as shown and described.
